DESIGN FOR A WATER HEATER

Georg Hegwein, Dessau, Germany, assignor to
Junkers & Co. G. m. b. H., Dessau, Germany

Application January 21, 1936, Serial No. 60,704
In Germany September 16, 1935

Term of patent 7 years

To all whom it may concern:

Be it known that I, Georg Hegwein, a citizen of Germany, residing at Dessau, State of Anhalt, Germany, have invented a new, original, and ornamental Design for Water Heaters, of which the following is a specification, reference being had to the accompanying drawing, forming a part thereof.

Fig. 1 is a front elevation of a water heater showing my new design.

Fig. 2 is a top plan view thereof.

I claim:

The ornamental design for a water heater, as shown.

In testimony whereof I affix my signature,

GEORG HEGWEIN.
